UNITED STATES PATENT OFFICE.

THOMAS W. PRITCHARD, OF WATERBURY, CONNECTICUT, ASSIGNOR TO THE STEELE & JOHNSON MANUFACTURING COMPANY, OF SAME PLACE.

SHADE OR GLOBE HOLDER.

SPECIFICATION forming part of Letters Patent No. 449,171, dated March 31, 1891.

Application filed October 25, 1890. Serial No. 369,304. (No model.)

To all whom it may concern:

Be it known that I, THOMAS W. PRITCHARD, a citizen of the United States, residing at Waterbury, in the county of New Haven and 5 State of Connecticut, have invented certain new and useful Improvements in Shade or Globe Holders; and I do hereby declare the following to be a full, clear, and exact description of the invention, such as will enable others skilled in the art to which it appertains 10 to make and use the same.

My invention is adapted to all classes of fixtures in which a shade or globe is engaged by a suitable holding-ring and the ring and 15 shade are secured to a fixture by a clasping-ring, the most important use being in connection with incandescent electric lights; and my invention has for its object to produce a stronger and more rigid construction without 20 increasing the cost of production.

With this end in view I have devised the simple and novel construction which I will now describe, referring by numerals to the accompanying drawings, forming part of this 25 specification, in which—

Figure 1 is a plan view of the blank which constitutes the clasping-ring and the arms, and Figs. 2 and 3 are respectively a side elevation and an inverted plan view of the holder 30 complete.

My improved shade or globe holder embodies the three essential elements commonly found in this class of holders—to wit, a shade or globe ring denoted by 1, a clasping-ring 35 denoted by 2, and arms 3, which connect the shade or globe ring to the clasping-ring. It will of course be apparent that in use the strain upon the holder comes almost entirely 40 at the points at which the arms are connected to the clasping-ring.

My present construction gives great strength at just the point where it is required with but a single thickness of metal and without riveting at that point. Heretofore it has been 45 common to rivet one or more of the arms to the clasping-ring. This has been found objectionable for two reasons. In the first place when the holders give out it is almost invariably by a loosening of the rivets at this 50 point, and in the second place the riveting of

the arms to the clasping-ring gives to the holder a clumsy and awkward appearance, which is objectionable to the trade, and which it is greatly desired to avoid. Still another consideration, which is by no means unimportant to the manufacturer, is that the riveting together of parts increases the amount of time consumed in assembling, and thereby adds considerably to the cost of production. 55 In another form the arms have been made integral with the shade or globe ring and provided with an attaching neck or socket to hold an independent spring clasping-ring. The special object of this construction is to make the holder lighter, stronger, more graceful, and at the same time to effect an important saving in the cost of manufacture. 60

The objects to be attained are, first, strength and rigidity; second, a light and graceful appearance, and, third, a construction that will 65 match up fairly well in blanking out, so as to make as little scrap as possible.

In my improved holder I use but two arms to connect the shade-ring with the clasping-ring, (another arm may of course be used, if 70 preferred,) both arms being formed integral with the ring itself, so that in use the strain at the point of connection with the clasping-ring is upon the arms transversely, so that it is practically impossible for them to spring 75 out of place to any appreciable extent. The shade-ring is made angular in cross-section, as usual, and is provided with lugs 4 to receive screws 5, which hold the shade or globe in place. I also preferably form enlargements 80 6 directly opposite each other on the upper side of the ring for the purpose of strengthening the attachment of the arms. The clasping-ring and arms I blank out in a single piece from sheet metal, the form of the blank 85 being clearly shown in Fig. 1. The portion to form the ring is a straight strip, from which the arms extend. At the ends of the blank enlargements 7 are formed having holes, one of which is threaded to receive a clasping- 90 screw 8, said screw passing freely through the other hole. At the ends of the arms are enlargements 9, also having holes. In blanking 95 out the blanks are of course matched up, so that the amount of scrap is reduced to the 100

minimum. After blanking out the rings and arms are curved to the required shape and enlargements 7 and 9 are bent outward at the required angle. In assembling, the shade-
5 ring and the arms are rigidly secured together by rivets 10, passing through enlargements 6 and 9.

The operation of my novel shade or globe holder is precisely the same as those in common use. The clasping-ring is placed about the fixture to which it is to be secured and locked there by tightening-screw 8 in enlargements 7.

Having thus described my invention, I
15 claim—

1. A shade or globe holder consisting of a suitable shade or globe ring and a clasping-ring and arms blanked out in a single piece, the arms being riveted to the shade-ring and
20 the clasping-ring provided with enlargements at its ends, and a clasping-screw passing

through one enlargement and engaging the other, by which the holder is secured in place.

2. A shade or globe holder consisting of a suitable ring, to which the shade or globe is secured, and which is provided with enlargements 6, and a clasping-ring and arms 3, blanked out in a single piece, the clasping-ring having at its ends enlargements 7, one of which is threaded to receive the clasping-
25 screw, and the arms having at their lower ends enlargements 9, bent to correspond with enlargements 6, the arms and shade-ring being rigidly secured together by rivets passing through the enlargements.

In testimony whereof I affix my signature in presence of two witnesses.

THOMAS W. PRITCHARD.
